DESIGN FOR A SHOE

Myron S. Goldman, St. Louis, Mo., assignor to Valley Shoe Corporation, St. Louis, Mo., a corporation of Missouri

Application January 21, 1935, Serial No. 54,957

Term of patent 3½ years

To all whom it may concern:

Be it known that I, Myron S. Goldman, a citizen of the United States, residing at the city of St. Louis, State of Missouri, have invented a new, original, and ornamental Design for a Shoe, of which the following is a specification, reference being made to the accompanying drawing, forming a part thereof in which Figure 1 is a plan view of a shoe, with the lacing omitted therefrom, and Figure 2 is a perspective view of a shoe embodying my design.

I claim—

The ornamental design for a shoe, substantially as shown and described.

MYRON S. GOLDMAN.
